US0D1026622S

(12) **United States Design Patent** (10) Patent No.: **US D1,026,622 S**
(45) Date of Patent: ** May 14, 2024

(54) **BRACKET**

(71) Applicants: **Taylor M. Hong**, Honolulu, HI (US);
Craig J. Iinuma, Aiea, HI (US)

(72) Inventors: **Taylor M. Hong**, Honolulu, HI (US);
Craig J. Iinuma, Aiea, HI (US)

(**) Term: **15 Years**

(21) Appl. No.: **29/875,698**

(22) Filed: **May 9, 2023**

Related U.S. Application Data

(62) Division of application No. 29/790,777, filed on Dec. 14, 2021, now Pat. No. Des. 990,289.

(57) **CLAIM**

The ornamental design for a bracket, as shown and described.

DESCRIPTION

FIG. 1 is a top-front perspective view of a bracket showing the new design;

FIG. 2 is a bottom-rear perspective view of the bracket;

FIG. 3 is a top view of the bracket;

FIG. 4 is a bottom view of the bracket;

FIG. 5 is a left side view thereof, with the right side view being a mirror image of the left side of the bracket;

FIG. 6 is a front view of the bracket; and,

FIG. 7 is a back view of the bracket.

The bracket is shown with symbolic breaks along its length in FIGS. 1-7. The appearance of any portion of the article between the break lines forms no part of the claimed design.

1 Claim, 5 Drawing Sheets
